ATTORNEY.

UNITED STATES PATENT OFFICE.

THOMAS M. MOORE, OF RUSK, TEXAS.

PLOW.

SPECIFICATION forming part of Letters Patent No. 332,206, dated December 8, 1885.

Application filed March 25, 1885. Serial No. 160,133. (No model.)

To all whom it may concern:

Be it known that I, T. M. MOORE, a citizen of the United States of America, residing at Rusk, in the county of Cherokee and State of Texas, 5 have invented certain new and useful Improvements in Plows, of which the following is a specification, reference being had therein to the accompanying drawings.

This invention has for its object to provide 10 a convertible plow and cultivator to meet the requirements of the particular kind of work to be done, a further object also being to permit the adjustment of the handles, whereby the attendant or plowman may follow or walk directly 15 behind or in the furrow of the plow; and the invention consists of the combinations of parts and their construction, substantially as hereinafter fully set forth and claimed.

In the accompanying drawings, Figure 1 is 20 a side view of my improvement with the appliance in position used in applying a cultivator-shovel, "bull-tongue," or "sweep" to the standard. Fig. 2 is a similar view with the said appliance thrown back or elevated 25 out of the way, as when the ordinary share and mold-board are used. Fig. 3 is a plan view of the same, showing in particular the handle-adjusting contrivance. Figs. 4 and 5 are detail views of the cultivator-shovel appliance 30 and the handle-adjusting contrivance, respectively. Fig. 6 is a side view of my invention, taken on the reverse side to that of Fig. 2, with the handles removed; and Fig. 7 is an enlarged sectional view taken beneath 35 the plow-beam, with the shovels removed.

In carrying out this my invention I employ in connection with the usual beam, A, and the plow or shovel standard B, connected to the latter, the brace-bar C, whose upper end is 40 bolted to the rear end of the beam A, while its lower end is disposed opposite to and a short interval from the lower end of the standard B, the upper surface of said latter end of brace-bar being arranged in a plane slightly 45 lower than the same surface of the standard, to provide with the latter a seat for the inclined surface of the share and mold-board. Between the extreme lower ends of the standard and its brace-bar is disposed a separating 50 or spacing stud, a, said stud being connected

to said brace-bar and countersunk in said standard. Upon the upper surface of the lower ends of the standards and brace is secured the plowshare D, while upon the same surface of the brace and standard, and abutting against the upper edge of the plowshare, is secured 55 the mold-board D', both the share and mold-board being connected thereto by bolts b, with one end countersunk in the share and mold-board, respectively, while said bolts are passed 60 bodily through the space between the brace-bar and standard, and secured to the under side of the latter by nuts, which permit the ready removal of the share and mold-board, when it may be desired to exchange them for 65 a cultivator or shovel, bull-tongue, or sweep, according to the particular class of work to be done. To the left-hand side of the standard, at its extreme lower end, is fastened by the bolt d the landside E, said bolt being countersunk 70 in the latter at one end and passed bodily through coincident apertures in said standard and in the brace-bar, and secured thereto by a nut, whereby also the landside may be readily removed for the same purpose, recited 75 in connection with the description of the removal of the plowshare and mold-board.

F F' is a jointed or articulated sectional bar with one section pivoted to a bolt between the brace-bar and standard B C, near the point of 80 divergence of said bar and standard, the outer section or arm of which sectional bar, when the implement is converted into a cultivator or used for an analogous purpose, (in which case, as before stated, the plowshare, mold-board, and the landside are removed,) rests upon the lower portion of the brace-bar C to level the latter with the standard B at that point, in order to provide a broad supporting-surface for the cultivator-shovel, bull-tongue, 85 or sweep replacing the plow, which disposition of the said sectional bar or appliance is seen in Fig. 1. The cultivator-shovel, or either of the latter two implements, when used, is secured in position by the bolt e, as seen in 90 the said Fig. 1. It is obvious that when the plow is to be again placed in position, or when used, the said sectional bar can be swung up and back out of the way of the mold-board of 95 the plow, as seen in Fig. 2.

- G is a counter brace-bar with its vertical straight portion held firmly to one side of the beam A, its extreme upper end being bolted above said beam to the same end of the standard B, while below said beam said counter brace-bar is again bolted to said standard B. From the latter point said counter brace-bar G is inclined a short distance inwardly and rearwardly, and then again rearwardly and 10 downwardly, as at f, the said latter portion, f, being provided with a slot, f', through which is inserted a bolt, securing it to the primary brace-bar C.
- H H are the handles, which are secured together and disposed convergently, their lower nearly-meeting ends having their connecting bolt g passed through the slot f' of the counter brace-bar G, the function of which will appear hereinafter.
- 20 Through the rear end of the beam A passes a bolt, h, upon the upper projecting screw-thread end of which are placed two clamp-plates or disks, i i, having opposite grooves, i', which receive a round, I, of the handles, 25 said clamp plates or disks being held firmly upon said round by a nut screwed upon the said bolt. It is obvious that by loosening the nut, permitting the loosening of the disks or plates, and by unscrewing the nut of the bolt 30 connecting the lower ends of the handles to the slotted plate, the handles can be readily shifted laterally or adjusted to suit the inclination or height required, according to the height of the attendant or plowman, the 35 grooved clamp-plates or disks and the embraced round of the handles serving as fulcrum and pivot, respectively, for the handles, which latter thus become a lever. The lateral shifting of the handles is to enable the plowman to 40 walk directly in line with and in rear of the plowshare, bull-tongue, or sweep, as the case may be. By means of said connection between

the beam and the handles, together with the slotted connection between the handles and the counter brace-bar, before described, the further adjustment of the handles vertically can be effected, whereby they can be raised or lowered to accommodate the height of the plowman or attendant. 45

Having thus fully described my invention, 50 what I claim, and desire to secure by Letters Patent, is—

1. In a plow, the combination, with the beam and the standard, of the inclined brace and the sectional or jointed bar arranged to 55 fold upon the lower part of the said brace, substantially as and for the purpose set forth.
2. In a plow, the handles having a round thereof secured between two grooved clamp-plates held by a nut on a bolt, and their lower 60 convergent ends connected and capable of vertical adjustment by a bolt passed through a slot of the counter brace-bar, substantially as shown and described.
3. In a plow, the combination, with the 65 beam, the handles, the brace-bar, and the slotted counter-brace, of the grooved clamp-plates and the round connected to the handles, together with adjusting and holding bolt passed through the lower convergent ends of the handles and the slot of the counter brace-bar, substantially as and for the purpose specified.

4. In a plow, the sectional or jointed bar connected between the standard and the inclined brace-bar, and arranged to fold upon 70 the lower part of said brace-bar, substantially as shown, and for the purpose set forth.

In testimony whereof I affix my signature in presence of two witnesses.

THOMAS M. MOORE.
